UNITED STATES PATENT OFFICE.

GEORGE M. DUVALL, OF AUBURN, MASSACHUSETTS, ASSIGNOR OF ONE-HALF TO
WILLIAM A. DUVALL, OF AUBURN, MASSACHUSETTS.

JAR-OPENER.

1,111,998.

Specification of Letters Patent. Patented Sept. 29, 1914.

Application filed February 27, 1909. Serial No. 480,432.

To all whom it may concern:

Be it known that I, GEORGE M. DUVALL, a citizen of the United States, residing at Auburn, in the county of Worcester and 5 Commonwealth of Massachusetts, have invented a new and useful Improvement in Jar-Openers, of which the following is a specification accompanied by drawings, forming a part of the same, in which—
10 Figure 1 is a side view of my improved jar opener in position to open a jar, and Fig. 2 is a plan view of Fig. 1.
Similar reference figures refer to similar parts in the different views.
15 My invention relates to openers for jars in which a gasket or washer is employed to make an air tight joint between the jar and its cover, and comprises means for removing the covers after they have been unfastened, and it consists in the construction and 20 arrangement of parts as hereinafter described and pointed out in the annexed claims.

In the use of jars designed for the preservation of material which would be injured by continued exposure to the air, such as fruit, the cover of the jar is usually closed while the contents are hot, and is firmly fastened with a gasket or washer of rubber or 30 similar material between the cover and the top of the jar in order to form an air tight joint, so that upon the cooling of the contents a partial vacuum is formed within the jar. As a result, the cover of the jar is 35 subjected to more or less air pressure tending to keep it in contact with the washer, so that it is necessary to open a communication between the outside air and the inside of the jar to equalize the air pressure before 40 the cover can be removed. In addition, it frequently occurs that the washer is attached to jar and cover by the adhesive character of the contents of the jar, and a certain amount of force is necessary to accomplish 45 the separation of jar and cover.

In my improved jar opener I provide means for piercing the washer to let air into the jar, combined with means for exerting the necessary force to detach the cover.
50 Referring to the accompanying drawings, 1 is a jar constructed of glass or similar material, provided with a cover 2, and with a washer or gasket 3 between the cover and the top of the jar. A wire fastening 4, 55 shown in dotted lines in Fig. 1, is provided

to hold the cover tightly in contact with the washer 3 in the well known manner.

In order to separate the cover from the jar after the wire fastening is in the position shown in Fig. 1, I provide a stationary three armed member 4^a having radial arms 5, with their tips bent downward forming clamps 6, arranged to contact with the periphery of the cover. The member 4^a is also provided with a radial arm 7 to project over the edge of the cover, extending horizontally and bent downward at 8 and outward at 9, to provide a bearing surface in the plane of the washer 3 for a lever 10 pivoted at 11 to the arm 7 beyond the outward bend 9. 65 The inner or shorter arm 12 of the lever 10 is arranged to be longer than the distance from the pivot 11 to the edge of the washer 3, and is provided with a knife edge 13 preferably slightly curved, to adapt it to be crowded between the washer 3 and the top of the jar.

The pivoted lever 10 is placed at an angle to the arm 7 and the member 4^a is placed upon the cover 2 of the jar, as shown in Fig. 80 2. Movement of the lever 10 to the position indicated by the dotted lines 14 in Fig. 2 will cause the knife edge 13 to be crowded, preferably, between the washer 3 and the top of the jar, thereby opening communication between the inside of the jar and the outside air, and equalizing air pressure upon the inside and outside of the cover. With the lever 10 in the position shown by dotted lines 14 in Fig. 2, the outer end 15 may 85 be raised and the cover lifted from the jar, and, in this position, it will supply sufficient leverage to insure the removal of the cover, even though the cover, jar and washer are stuck together by the adhesive character of 90 the contents of the jar.

The entering end of the lever 10 is slightly beveled and acts as a wedge to lift the edge of the cover which is held between the lever 10 and the supporting three armed member 4^a, enabling the device to serve as a handle for holding the cover.

It will be observed that the entry of the beveled edge 13 below the cover 2 has a decided tendency to force said cover upwardly, 105 away from the upper end of the jar, thereby facilitating the entrance of air below said cover and permitting the subsequent removal of the cover from the jar. Furthermore, the effect of the aforesaid entry of the 110

beveled edge 13 is to press the jar cover laterally, into closer contact with the claws 6, and also to crowd said cover between said beveled edge and the adjacent arm 7 of the 5 three-armed supporting member 4^a, whereby the said cover is retained and firmly gripped by the jar opener even after removal of the said cover from the jar. Furthermore, as clearly seen in Fig. 1, the downwardly bent 10 claws 6 of the radial arms 5 are extended below the plane of the washer 3 and lever 10, whereby upon removal of the cover from the jar in the manner above described, the said claws 6 will act as supporting legs to 15 prevent the contact of the washer or cover with the stand or table on which it may be laid, and thus preclude the possibility of access of foreign matter to the face of the cover or washer, and at the same time prevent 20 any of the contents of the jar adhering to the inside of the cover from being smeared over the stand or table.

I claim,

1. A jar opener, comprising a supporting 25 member adapted to rest on the top of the jar cover, said supporting member provided with downwardly extending arms to engage the cover, and also provided with a downwardly extending portion bent to form a 30 bearing surface in the plane of the top of the jar, and a lever pivoted on said bearing

surface, one arm of said lever provided with a beveled edge adapted to enter between the jar and cover to crowd the cover against the supporting member, whereby said cover 35 is gripped and carried by said jar opener upon removal from the jar.

2. A jar opener, comprising a supporting member adapted to rest on the top of the jar cover, said supporting member provided 40 with arms extending downwardly to engage the cover, and also provided with a downwardly extending portion bent to form a bearing surface in the plane of the top of the jar, a lever pivoted on said bearing surface, said lever having a beveled edge at one end adapted to be crowded between the top of the jar and the cover, whereby to retain said cover between the said lever and said supporting member, the said arms of 45 the supporting member extending below and beyond the plane of the top of the jar to support said cover in a raised position upon its removal, in conjunction with the opener, from the jar. 55

Dated this twentieth day of February, 1909.

GEORGE M. DUVALL.
